UNITED STATES PATENT OFFICE.

ARTHUR PEART HOLDEN AND PHILIP MORGAN, OF TORONTO, ONTARIO, CANADA.

THREAD-MILLING MACHINE.

1,215,804.

Specification of Letters Patent. Patented Feb. 13, 1917.

Application filed May 29, 1915. Serial No. 31,307.

To all whom it may concern:

Be it known that we, ARTHUR PEART HOLDEN and PHILIP MORGAN, both of the city of Toronto, in the county of York and Province of Ontario, Dominion of Canada, have invented certain new and useful Improvements in Thread-Milling Machines; and we hereby declare that the following is a full, clear, and exact description of the

10 same.

In the manufacture of high explosive shells, it is necessary to bore a "blind" hole centrally in the base of the shell and thread it for the reinforcing plug which receives 15 the force of the firing charge, no variation being permitted in the diameter of the hole, or the perfection of the thread.

The present machine has been particularly designed for automatically and correctly centering the partly-finished shell to 20 the axis of the revolution of the chuck which operates to simultaneously feed the work in an axial direction during its revolution and determine the pitch of the thread 25 while the milling operation is being performed, the revolution of the chuck on the completion of the thread being automatically arrested, and for perfectly milling a completed thread to the bottom of a "blind" 30 hole of this character, so that the threaded stem of the reinforcing plug will completely fill it to the satisfaction of the most critical ammunition inspection requirements.

In the drawings:

35 Figure I, is a side elevation of the machine partly in section, showing the assembled relation of the parts with a partly-finished shell in the chuck;

40 Fig. II, is a section on a larger scale than Fig. I, of the cylindrical chuck and its related parts;

Fig. III, is an end elevation of the machine shown in Fig. I;

45 Fig. IV, is a plan view of part of the same;

Fig. V, is a perspective detail view, partly in section, showing the feed ring; and

50 Fig. VI, is a longitudinal section of a high explosive shell showing the reinforcing plug fitted to the base.

Like characters of reference refer to like parts throughout the specification and drawings.

55 In the manufacture of shell projectiles, each shell *a*, which is drilled and turned to the required size and shape, is provided in

the base *a'* with a blind hole *a''*, having a perfect thread *a³* from the inner to the outer end of the hole. This threaded hole must be of uniform diameter throughout its 60 length to form a tight fit with the threaded shank *b* of the reinforcing plug *b'*, so that the gas from the firing charge cannot penetrate between the wall of the hole and the shank.

65

Rapidity and accuracy are two important factors in the manufacture of this class of article, particularly during war periods, in order to maintain the supply of high-grade ammunition for the requirements at the 70 front.

In order to successfully carry on the manufacture of this type of shell, the milling machine is provided with a substantially cylindrical work holder or chuck *c* having 75 an axial bore *c'* therethrough of substantially corresponding shape and dimensions to the external shape and dimensions of the shell *a*, so that when the partly-finished shell *a* is inserted into the bore of the cylindrical 80 chuck, it will be automatically and accurately centered.

As shown in Fig. I, the base of the shell *a* is opposed to the milling tool *d*, and that part *c''* of the bore *c'* engaging the base *a'* of the shell serves as a positive stop to correctly locate or position the shell within the work holder and converges to form a clamping member for engaging that end of the 90 work.

The opposite end *c³* of the axial bore *c'* to the converging end *c''* is threaded to receive a hollow clamping member *e*, the inner end of the bore *e'* of the clamping member *e* being of a corresponding shape 95 to the nose *a⁴* of the shell *a*, and the outer surface of the clamping member *e* being threaded to engage with the threads of the end *c³* so that when the clamping member *e* is tightly screwed into the bore of the cylindrical chuck *c*, it will bind against the nose of the shell *a* and force the base of the shell against the converging part *c''* and lock the shell within the chuck, which then will 100 unitedly revolve with the chuck.

The chuck *c* is journaled in three bearings *f*, *f'*, *f''* supported by the frame *g*, and the outer surface of the chuck between the bearings *f*, *f'* is threaded as shown at *h*, of corresponding pitch to the thread *a³* to be milled in the blind hole *a''* in the base of the shell *a*.

105

110

Encircling the chuck c between the bearings f, f' , is a divided feed ring i having its bore threaded to correspond with and engage the thread h on the outer surface of the chuck c , the bearings f, f' preventing the lateral movement of the feed ring. As shown in Fig. V, the feed ring i consists of two members i', i'' , pivoted at one side to the flanges f^4 of the bearings f, f' , so that they can be swung into open or closed relation with the cylindrical chuck c for the purpose of disengaging the threaded surface i^3 of the bore of the feed ring from the threaded surface h of the cylindrical chuck, when it is desired to quickly move the chuck in the direction of the milling tool d .

Pivoted to the free end of the member i' is a bolt j which, in its operative position, enters between the forks j' of the member i'' . The bolt j , as shown in Fig. V, is provided with a nut k to engage the forks j' for the purpose of drawing the free ends of the members i', i'' together and bringing the threaded surface i^3 of the bore of the feed ring into engagement with the threads h of the cylindrical chuck. Splined on the cylindrical chuck c , between the bearings f, f' , is a worm wheel l partly covered by a guard casing q , and cut in the bore of the worm wheel and the perimeter of the chuck c , are keyways for the keys z which, while causing the united revolution of the worm wheel and chuck, permit the chuck to slide axially through the worm wheel, the lateral movement of the worm wheel being prevented by the bearings f, f' , which are located close to its side faces. The worm wheel l meshes with a worm l' mounted on a shaft l^3 , provided with a pulley l'' , and journaled near one end in a rocking bearing m , and at the other end in a movable bearing m' slidably connected to the frame g by a bolt m'' passing through an elongated slot m^3 in the bearing.

Bolted to the frame g is an arm o , to which is fulcrumed a lever o' having a shoulder o'' engaging a lip p on the movable bearing m' to support the bearing when holding the worm l' in mesh with the worm wheel l , and on the end of the chuck c is a collar p' having a flange p'' engaging the lever o' .

The starting position of the parts is that shown in Figs. I and II, the chuck c in this position being moved lengthwise to its limit of movement in the direction indicated by arrow, its further movement in that direction being arrested by the flange p' on the collar p abutting against the bearing f'' .

The flanged collar p, p' is provided with a stop pin q' and the bearing f'' is provided with a stop pin q'' , the chuck when coming to the starting position being turned in the direction indicated by arrow in Fig.

III, until the stop pin q' comes into engagement with the stop pin q'' so that the revolution of the chuck will always begin from the same place.

When the chuck has been positioned, as shown in Figs. I and II, the partly-finished shell a is placed in its bore c' . The hollow clamping member e is then inserted in the end of the chuck and tightened against the nose of the shell until the base of the shell is forced tightly against the converging part c'' of the bore of the chuck, the shell then being correctly centered and tightly clamped within the cylindrical chuck.

The milling tool d , fixed on a shaft d' mounted in bearings d'' movable lengthwise and laterally of the frame g , is then shifted to commence milling at the inner end of the blind hole a'' , motion being transmitted through the pulley d^3 to the shaft d' and milling tool d .

When the milling tool d has been correctly positioned, the worm l' is moved into mesh with the worm wheel l and the lever o' is moved into position to support the movable bearing m' for the worm and maintain the worm in mesh with the worm wheel while the milling operation is being performed.

When the worm is brought into mesh with the worm wheel, the revolution of the chuck and shell starts, and the milling tool commences to mill the thread in the blind hole a'' .

During the revolution of the chuck, the meshing of the threaded surface h of the chuck with the threaded surface i^3 of the feed ring i feeds the chuck in a direction away from the milling tool and not only causes the milling of the thread in the blind hole a'' corresponding in the pitch to that of the threaded surfaces h, i^3 , but also causes the pin q' to clear the pin q'' .

During this feed of the chuck c , the flange p' gradually works the lever o' outward, as shown in dotted lines in Figs. I and II, and ultimately disengages the shoulder o'' from the lip p .

When the shoulder is disengaged from the lip, the movable bearing m' drops into the position indicated in dotted lines in Figs. I and II, releasing the worm from mesh with the worm wheel and stopping the motion of the chuck, this stop motion being timed to correspond with the completion of the milling of the thread in the blind hole. The clamping member e is then removed and the threaded shell is withdrawn from the chuck, a fresh shell is inserted in the chuck, and the clamping member is replaced. To quickly move the chuck to its limit of motion in the direction of the milling tool d , the nut k is slackened on the bolt j , the members i', i'' of the feed ring are opened to disengage the threaded surface i^3 from

the threaded surface h , the chuck is then pressed in the direction indicated by arrow in Fig. I, until the flange p' engages the bearing f'' , and turned in the direction indicated by arrow in Fig. III until the stop pin q' engages the stop pin q'' and arrests its further turning movement.

5 The milling tool is then moved again to the inner end of the blind hole and the 10 worm is moved into mesh with the worm wheel to repeat the milling operation.

By means of this construction, a perfectly-formed thread can be rapidly milled in the blind hole, and without supervision, it being 15 only necessary for the operator to place the work in and remove it from the machine.

Having thus fully described the nature of our invention, what we claim as new and desire to secure by Letters Patent, is:—

20 1. A thread milling machine comprising a set of bearings, an axially-movable cylindrical work holder journaled therein having its outer surface threaded, threaded means engaging with the threaded surface of the work holder for causing its axial movement, a worm wheel mounted on the work holder, means for slidably securing the work holder to the worm wheel, a worm meshing with the worm wheel, journaled at one end 25 in a rockable bearing and at the other in a movable bearing, and a pivoted support for the movable bearing displaced therefrom by the chuck when it has reached the limit of movement in an axial direction.

30 35 2. A thread milling machine comprising a set of bearings, a cylindrical work holder journaled therein having its outer surface threaded, a clamp having its inner surface threaded to engage with the threaded surface 40 of the work holder, said clamp consisting of two clamping members located between two of the bearings, and a clamping bolt and nut closing them together, a worm wheel mounted on the work holder, a key 45 entered in a keyway in the worm wheel and work holder for slidably securing the work holder to the worm wheel, a worm meshing with the worm wheel, journaled at one end in a rockable bearing and at the other in a movable bearing, and a pivoted support for the movable bearing displaced therefrom by the chuck when it has reached its 50 limit of movement in an axial direction.

3. A thread milling machine comprising 55 an axially-movable hollow rotatable work holder having an axial bore tapering toward one end, clamping means within the bore to hold the work therein, a gear wheel to which the work holder is splined so that 60 it is rotated by the worm wheel, but is free to move axially through it, the outer surface of the work holder having a feed thread thereon, and means engaging with the feed thread to cause the axial movement of the 65 work holder during its rotation.

4. A thread milling machine comprising a hollow rotatable work holder having an axial bore tapering toward one end, a clamping nut adjustable in the other end of said bore, coöperating with the tapering end to correctly position and securely hold the work within said holder, a bearing in which the work is journaled and through which it is axially movable, a gear wheel splined to the work holder so that as it is rotated the work holder will move axially through it, a feed thread on the external surface of the work holder, and means engaging with the feed thread to cause the axial movement of the work holder as it rotates.

5. A thread milling machine comprising an axially-movable hollow rotatable work holder having an axial bore, clamping means to hold the work therein, a worm wheel splined to the work holder so that the work holder is rotated by it and is free to move axially through it, a worm meshing with the worm wheel, a movable bearing for the worm, and a pivoted support for the movable bearing, displaced therefrom by the work holder when it has reached the limit of movement in an axial direction.

6. A thread milling machine comprising a bearing, an axially-movable cylindrical work holder journaled therein having a feed thread on its outer surface, threaded means engaging with the feed thread of the work holder for causing its axial movement, a worm wheel mounted on the work holder, means for slidably securing the work holder to the worm wheel, a worm meshing with the worm wheel journaled at one end in a movable bearing, and a pivoted support for the movable bearing displaced therefrom by the work holder when it has reached the limit of movement in an axial direction.

7. A thread milling machine comprising a bearing, a cylindrical work holder journaled in and axially movable through the bearing, a worm wheel splined to the work holder so that the work holder is free to move axially through it, a worm meshing with the worm wheel to cause the rotation of the work holder, means for effecting the movement of the work holder in an axial direction, and means for disengaging the worm from the worm wheel when the work holder has reached its limit of axial movement.

8. A thread milling machine comprising 120 a stationary bearing, a cylindrical work holder journaled in and axially movable through the bearing, a worm wheel splined to the work holder so that the work holder will be rotated by it and will be free to move axially through it, a worm meshing with the worm wheel, a movable bearing in which one end of the worm is journaled, and a pivoted support for the movable bearing, displaced therefrom by the work holder 125 130

when it has reached its limit of movement in an axial direction.

9. In a thread milling machine, the combination of a bearing, an axially-movable work holder rotatable therein, a worm wheel splined to the work holder so that the work holder is axially movable through it, a worm meshing with the worm wheel, means causing the axial feed movement of the work holder, and means holding the worm in mesh with the worm wheel displaced by the work holder when it has reached the limit of its axial movement releasing the worm from the worm wheel.
10. In a thread milling machine, the combination of a bearing, an axially-movable work holder rotatable therein, a worm wheel splined on the work holder so that the work holder is axially movable through it, means for holding the worm wheel against axial movement, a worm meshing with the worm wheel, means causing the axial feed movement of the work holder, and means holding the worm in mesh with the worm wheel displaced by the work holder when it has reached the limit of its axial movement releasing the worm from the worm wheel.
11. In a thread milling machine, an axially-movable cylindrical work holder, means causing the axial feed movement of the work holder, a worm wheel splined on the work holder so that the work holder is axially movable through it, a worm meshing with the worm wheel, a movable bearing in which the worm is journaled, and a support for the movable bearing holding the worm in mesh with the worm wheel displaced by the work holder when it has reached the limit of its axial movement releasing the worm from the worm wheel.
12. In a thread milling machine, the combination of a bearing, an axially-movable cylindrical work holder rotatable therein, a

worm wheel splined on the work holder so that the work holder is axially movable through it, means preventing the movement of the worm wheel in an axial direction, a worm meshing with the worm wheel, a movable bearing in which the worm is journaled, and means holding the movable bearing to maintain the worm in mesh with the worm wheel displaced by the work holder when it has reached the limit of its axial movement releasing the worm from the worm wheel.

13. In a thread milling machine, the combination of a bearing, an axially-movable work holder rotatable therein, means for causing the axial feed movement of the work holder, a worm wheel splined on the work holder so that the work holder is axially movable through it, means preventing the movement of the worm wheel in an axial direction, a worm meshing with the worm wheel, a movable bearing in which the worm is journaled, and a pivoted arm, supporting the movable bearing holding the worm in mesh with the worm wheel displaced by the work holder when it has reached the limit of its axial movement and releasing the worm from mesh with the worm wheel.

14. In a thread milling machine, an axially-movable cylindrical work holder, a threaded member engaging with a thread of corresponding pitch on the exterior of the work holder for its axial feed movement, a worm wheel splined on the work holder so that the work holder is axially movable through it, a worm meshing with the worm wheel, and means holding the worm in mesh with the worm wheel displaced by the work holder when it has reached the limit of its axial movement releasing the worm from mesh with the worm wheel.

Toronto, May 10th, 1915.

ARTHUR PEART HOLDEN.
PHILIP MORGAN.
